VULCANIZER

Filed Dec. 10, 1930

John W. Barton *Inventor*

By S. E. Thomas *Attorney*

UNITED STATES PATENT OFFICE

JOHN W. BARTON, OF FLINT, MICHIGAN, ASSIGNOR TO BARTON PACKER COMPANY,
OF FLINT, MICHIGAN, A CORPORATION OF MICHIGAN

VULCANIZER

Application filed December 10, 1930. Serial No. 501,220.

This invention relates to vulcanizers and more particularly an apparatus for "spot" vulcanizing automobile tires, as shown in the accompanying drawings and described in the following specification and claims.

The primary object of the present invention is to provide the usual steam heated vulcanizer, comprising a steam chamber, an overhanging platen suspended from a manually adjustable screw shaft supported at the end of a swinging arm, in turn mounted upon a post rising above the steam chamber, with a plunger heated by the steam in the chamber and slideable in a cylinder extending through and integral with the wall of said chamber;—the plunger being actuated by a spring which forces it laterally against a receiving pad supported at the end of a goose-neck arm attached to the frame of the device;—a foot lever serving to withdraw the plunger from contact with the receiving pad as required to admit the parts to be vulcanized.

A further object of the invention is to support the pad receiving the thrust of the plunger upon a universal joint that it may thereby flex and thus automatically adapt itself to the plunger and the parts to be vulcanized.

Another feature of the invention is the construction of the frame supporting the pad whereby relatively large outer casings for trucks or like vehicles may be inserted between the plunger and the receiving pad for vulcanizing side cuts and bruises, not readily accessible.

With the foregoing and other objects in view which will appear as the description proceeds, the invention further resides in the combination and arrangement of parts and in the details of construction herein-after described and claimed, it being understood that changes may be made in the precise embodiment of the invention herein disclosed without departing from the spirit of the same.

In the drawings accompanying this specification:

Figure 1 is a side elevation with parts broken away and in section showing the spring

actuated plunger bearing against a receiving pad preferably mounted upon a wooden block secured to a ball and socket joint, supported at the end of a goose-neck member of the frame.

Figure 2 is a similar side elevation with parts broken away showing the plunger drawn from contact with the receiving pad due to the operation of a foot lever.

Figure 3 is a cross-sectional view through the steam chamber, taken on or about line 3—3 of Figure 2, showing the movable plunger housed within a cylinder integral with the walls of the steam chamber, the view also indicating diagrammatically an electric heating element supported below the steam chamber, and also a pressure gauge and relief valve connected with the steam chamber.

Figure 4 is a fragmentary detail on an enlarged scale of the safety or relief valve, taken on or about line 4—4 of Figure 3.

Referring now to the letters of reference placed upon the drawings:

A indicates a base plate from which rises a tubular standard B, at the top of which is secured a casting C, supporting a steam chamber D, having a flat upper surface or platen D¹, to receive the part to be vulcanized.

F indicates diagrammatically an electrical heating element.

G denotes a steam gauge connected through a pipe nipple with the steam chamber D and also with an electrical cut-out F¹,—indicated diagrammatically—the construction being such that upon excessive pressure in the steam chamber, the cut-out is automatically operated to open the circuit.

Supported upon a post H, mounted in brackets integral with the steam chamber, is a swinging arm I tapped to receive a manually operated screw shaft J, on the lower end of which is carried a platen K, adapted upon adjustment of the screw-shaft to engage parts to be vulcanized when placed upon the upper surface of the steam chamber.

The foregoing elements are of usual construction and form no part of the present

invention except as the same operate in conjunction with the features now to be described.

The steam chamber D is formed with a cylinder D^a, the wall of which is integral with the wall of the steam chamber.

L is a plunger slideable within the cylinder D^a having an integral rearwardly projecting end portion L^a, of relatively smaller diameter, extending through a cup-shaped casting M, bolted to the wall of the steam chamber.

N is a coiled spring bearing at one end against the wall of the cup-shaped member M, and at its opposite end against a shoulder formed by the enlarged portion of the plunger, forcing the plunger outwardly to the limit of its movement.

O is a bell-crank lever pivoted at O¹ to the upturned end of a cross arm P, bolted to the tubular standard B extending upwardly from the supporting base plate. One arm of the bell-crank lever engages a pin L¹ extending through the end portion L^a of the plunger, the other arm of the bell-crank lever is pivoted to a link bar Q, in turn connected with a treadle Q^a pivoted to the standard. The opposite end of the cross-arm P terminates in a goose-neck with a ball and socket connection R supporting a wooden block S to which is secured a pad T formed of rubber, leather or other suitable material to receive the thrust of the spring actuated plunger. By supporting the pad T upon a block including a ball and socket joint the pad is adapted to automatically adjust itself to irregularities in the surface of the parts being vulcanized—the wood block serving as an insulator against the transmission of heat.

The safety valve U shown in Figure 4, while forming no part of the present invention consists in a disc U^a supported in a steam line connected with the chamber and is adapted to fracture under predetermined pressure and thus automatically relieve the steam chamber of excess pressure.

Having now indicated the several parts by reference letters, the construction and operation of the device will be readily understood.

Steam having been generated by the heating element F in the chamber D to heat the plunger L, the outer end of the plunger is withdrawn from normal contact with the pad T through the operation of the treadle Q^a.

The parts to be vulcanized are then inserted between the pad and end of the plunger—the plunger actuated by the spring N closing over the parts upon withdrawal of the foot from the treadle. Upon the completion of the vulcanizing operation, the plunger is again withdrawn by actuating the treadle, thereby releasing the parts that have been vulcanized.

Having thus described my invention, what I claim is:

1. In an apparatus of the character described, a suitable supporting frame; a cylinder; a slideable plunger housed in the cylinder, whereby the plunger may be heated; a pad, to receive the thrust of the plunger supported by an arm comprising a portion of the frame; means for automatically forcing the end of the piston into abutting contact with the pad; and manually operated means for withdrawing the plunger from contact with the pad to receive and release the parts to be vulcanized.

2. In an apparatus of the class described, a supporting frame; a combined steam jacket and cylinder integral with and spaced from the walls of the steam jacket; a slideable plunger housed within the cylinder heated by steam within the jacket; a spring adapted to force the end of the plunger beyond the wall of the steam jacket; a pad to receive the thrust of the plunger; an arm secured to the frame fitted with a universal joint to which the pad is attached; and means including a treadle pivoted to the frame for retracting said plunger against the action of the spring, whereby the parts to be vulcanized may be inserted or removed as required.

3. In an apparatus of the character described, a base plate; a standard rising from the base plate; a cylinder integral with and spaced from the walls of a steam jacket surrounding the cylinder; means for supporting said steam jacket and cylinder upon the standard; a spring adapted to force the end of the plunger beyond the wall of the steam jacket; a pad to receive the thrust of the plunger, supported on an arm secured to the standard; a bell-crank lever pivoted to said arm, with one arm of the lever engaging the plunger; a treadle pivoted to said standard; and a link-bar connecting the treadle with the other arm of the bell-crank lever, whereby the plunger may be manually retracted against the action of the spring.

4. A structure as specified in claim 3, in combination with an electric heating element attached to said jacket for generating steam therein, and an automatic valve to relieve excess steam pressure in said chamber substantially as described.

5. A structure as specified in claim 1, including a wooden block interposed between the thrust pad and the supporting arm, substantially as and for the purpose described.

In testimony whereof, I sign this specification.

JOHN W. BARTON. 125
